(57) **CLAIM**

The ornamental design for landscape edging, as shown and described.

DESCRIPTION

FIG. 1 is a front elevation of landscape edging;

FIG. 2 is a top plan of the landscape edging sole of FIG. 1;

FIG. 3 is a bottom plan of the landscape edging of FIG. 1;

FIG. 4 is a rear elevation of the landscape edging of FIG. 1;

FIG. 5 is a right side elevation of the landscape edging of FIG. 1;

FIG. 6 is a left side elevation of the landscape edging of FIG. 1; and,

FIG. 7 is a detail of FIG. 2, showing surface contour and texture typical of front, top, and rear surfaces of the landscape edging.

The features bounded by dashed or broken lines (originally made with red felt tip marker) indicate environmental or other structures that form no part of the claimed design.
